UNITED STATES PATENT OFFICE.

JESSE T. HALL, OF CHICAGO, ILLINOIS.

DESIGN FOR A FOOT-REST FOR BICYCLE-PEDALS.

SPECIFICATION forming part of Design No. 27,304, dated July 6, 1897.

Application filed May 6, 1897. Serial No. 635,430. Term of patent 14 years.

To all whom it may concern:

Be it known that I, JESSE T. HALL, a citizen of the United States, residing at Chicago, in the county of Cook and State of Illinois, have invented and produced a new and original Design for a Foot-Rest for Bicycle-Pedals; and I do hereby declare the following to be a full, clear, and exact description thereof, reference being had to the drawings, forming a part thereof, in which—

Figure 1 is a top plan view, and Fig. 2 a side elevation.

The principal feature of my design is comprised in the elliptical curves AA in the edges of the foot-rest plates BB, forming the tread-

surfaces of the pedal. These curves stop short of the respective ends of the plates BB, the edges having straight lines C for the rest of the way to the ends of the spindle-sleeve C'.

A second feature of the design is the longitudinal slots or openings D in the sides of the foot-rest plates, as shown in Fig. 2.

What I claim is—

The design for a foot-rest for bicycle-pedals, substantially as herein shown and described.

JESSE T. HALL.
